TRANSFORMER TERMINAL.

Application filed May 7, 1923, Serial No. 637,079, and in Great Britain May 30, 1922.

Our invention relates to terminals for electrical transformers and in particular to terminals for transformers which are to be located out of doors or in exposed situations although the improved terminals can also be employed with transformers located under cover, that is to say under ordinary conditions of use.

In electrical transformers as at present generally constructed for outdoor use all tappings for the windings are brought to the oil level but only one from each winding is extended through the cover of the tank or casing. Consequently when it is desired to change a connection from one tapping to another the tank cover has to be removed.

Transformer terminals in which a plurality of leads or tappings pass through a single insulating bushing have already been employed but such terminals were not weather-proof or suitable for use in exposed situations.

An object of the present invention is to provide an improved construction of terminal of the kind above mentioned which will be weather-proof and not readily affected by external conditions so that it may be used in exposed situations where transformers are located in the open and not under cover.

With this object in view according to the invention the improved terminal comprises a substantially cylindrical insulating bushing containing a plurality of sockets insulated from each other and equi-distantly spaced from a common center with a removable cap carrying a plug adapted to make electrical connection with any one of said sockets. The removable cap is adapted to fit over the end of the bushing and to be rotated about an axis passing through the common centre of the sockets so that the plug can be caused to engage with any desired socket. In some cases the cap may be provided with two or more plugs one of which is adapted to engage with a centrally located socket in the insulating bushing.

In order that the invention may be more clearly understood and readily carried into practice, reference will now be made to the accompanying drawings wherein two constructional forms are illustrated by way of example:

Figs. 1 and 2 are respectively vertical 55 medial section and plan views of one form and

Figs. 3 and 4 similar views of the other form, the last named with the cap removed, with the electrical connections between 60 same and a transformer indicated diagrammatically.

In each form illustrated the terminal comprises a substantially cylindrical hollow body portion 5 of porcelain or other suitable insulating material having on the part intended to be located outside the transformer tank or casing a number of sheds 6 and a circumferential groove 7 adjacent the end thereof. A number of metal sockets 8 70 corresponding to the number of tappings or leads from each winding of the transformer are embedded in cement 9 near the end of the body portion of the terminal and arranged on the circumference of a circle concentric with said body portion. The terminal cap 10 is conveniently formed of sheet metal and has oppositely disposed internal projections 11 thereon engaging the circumferential groove 7 in the body portion of 80 the terminal and carries a plug 12 in such a position as to be adapted to engage with any one of the sockets 8 in accordance with the position to which the cap is rotated before it is sprung into position on the body 85 portion and which terminates, above the cap, in a screwed portion carrying a wing-nut 13.

The construction illustrated by Figs. 1 and 2 is adapted for use in connection with 90 a single phase or star connected three phase transformer both of which are represented diagrammatically at 14 the former by the full and the latter by both full and dotted lines, the cap 10 being connected by means 95 of the wing-nut 13 to an outgoing conductor which it is desired shall be connected to the winding of a leg of the transformer and the sockets 8 connected to the end 15 and to the several tappings 16, 17 of the said winding. 100 It will be obvious that by removing the cap and rotating it to the necessary position and then replacing same, connection can be made from the outgoing conductor to any one of the tappings desired.

The construction illustrated by Figs. 3 and 4 is specially adapted for use with a delta-connected three-phase transformer which is

illustrated diagrammatically at 18, an additional central socket 19 being provided in the body portion and an additional central plug 20 in the cap. The socket 19 is connected to the end 21 of one phase winding of the transformer and the sockets 8 to the end 22 and to tappings 23, 24 from another phase winding of the transformer. It will be apparent that by rotating the cap to various positions an outgoing conductor connected thereto by means of the wing-nut 13 may be connected with the end of one phase winding and any one of the tappings from the other phase winding.

With two or three terminals such as hereinbefore described external phase conductors may be connected to the phase windings of a single- or three-phase transformer in such manner as to include any desired portion of the phase windings as permitted by the tappings.

It will be seen that the cap 10 protects the terminal ends of the tappings of the transformer windings and a weather-proof construction is readily obtained. Removal and replacement of the cap 10 is easily effected owing to the inherent resilience of the material of which it is made or, alternatively, the projections 11 which engage in the circumferential groove 7 may be resiliently mounted or any other suitable construction may be adapted to permit removal and replacement of the cap.

The improved terminal construction is not

limited to three-phase transformers, and may obviously be employed with either indoor or outdoor apparatus.

Having now particularly described and ascertained the nature of our said invention and in what manner the same is to be performed, we declare that what we claim is:—

1. A terminal for an electrical transformer comprising an insulating bushing having a plurality of sockets therein insulated from one another and spaced equidistantly from a common center and an adjustable cap carrying a terminal plug adapted to selectively make electrical connection to any of the said sockets, the said cap being constituted to overlap the end of the bushing and shed moisture clear of the upper end of the bushing.

2. A terminal for an electrical transformer comprising an insulating bushing having a plurality of sockets therein insulated from one another and spaced equidistantly from a common center and an adjustable cap carrying a terminal plug adapted to selectively make electrical connection to any of the said sockets, the said cap being constituted to seal the end of the bushing against the entrance of moisture.

In testimony whereof, we have hereunto subscribed our names this 18th day of April, 1923.

JOHN BENTLEY HANSSELL.
BENEDICT BEESLEY.
